UNITED STATES PATENT OFFICE.

THOMAS BATTY, OF BROOKLYN, NEW YORK.

MEANS FOR REDUCING TOPSAILS.

Specification of Letters Patent No. 17,616, dated June 23, 1857.

To all whom it may concern:

Be it known that I, THOMAS BATTY, of the city of Brooklyn, in the county of Kings and State of New York, have invented a new and useful Improvement for Reducing the Topsails and Courses of Ships and other Vessels Preparatory to Reefing; and I do hereby declare that the following is a full, clear, and exact description of the same, reference being had to the accompanying drawings, forming part of this specification, in which—

Figure 1, is a front view of a topsail having my improvement applied, representing the sail fully spread. Fig. 2, is a similar view representing the sail with the yard lowered ready for reefing. Fig. 3 is a side view representing the sail with the yard lowered as in Fig. 2 and the edges of the sail drawn close to the yards ready for tying the reef points. Fig. 4, is a top view corresponding with Fig. 3.

Similar letters of reference indicate corresponding parts of the several figures.

A, is the lower mast; B, the topmast; C, the lower yard, and D, the topsail yard.

E is the sail which is or may be attached to the yards at its head and foot in the usual manner.

a, a, are reef bands, and b, b, strengthening bands.

F, is the topsail halyard applied in the usual manner.

G, G, G, are the reef pennants attached to the edges of the sail at the ends of the reef bands and running up over the front of the yard, through flat blocks c, c, on the top of the yard near the mast, and thence down to the deck.

H, H, H, are what I term bunt pennants, of which I have represented three to correspond with the number of pairs of reef pennants G, G, G, said bunt pennants being attached in the center of the width of the sail, 45 in line with the connecting points of the reef pennants and when the sail is strengthened by the reef bands a, a, and passing up the front of the sail through holes in a crane-neck formed piece of metal I, which is 50 cured to the top of the yard at the center of its length and opposite the mast, and projects over the front of the yard, and which 55 contains separate holes e, e, e, through which the bunt pennants pass upward to be secured to the upper part of the topmast or to the cross trees. The crane-neck piece I, also

assists in preventing the bellying out of the sail as it is lowered, as will be presently explained.

At the connection of the bunt pennants 60 with the sail, metal rods of from two to four feet in length, represented by dotted lines at f, f, f, Figs. 1 and 2, are sewed into the sail with bands, to constitute stretchers. These, however, are not indispensable. 65 The bunt pennants are severally of such length that when the sail is close reefed as shown in Fig. 2, they are taut, hence the bunt pennant of the lower reef is always 70 taut whether the sail is fully spread, or whether it is reefed, but those belonging to the upper reefs are slack when the sail is spread.

The operation of reducing sail is as follows: 75 Suppose the sail to have been fully spread and it be desired to close reef it. The yard is first lowered easily, and then all the reef pennants are hauled tight to draw the edges of the sail close up to the yard, which causes the bunt of the sail to be plaited between the 80 front of the yard and the still extended portion of the sail as is shown in Figs. 3 and 4. As the yard is lowered the bunt of the sail is 85 prevented by the position of the bunt pennants from filling with wind, and bellying on so as to be at times unmanageable as it does with the ordinary rig, and with many of the recently patented rigs, as the bunt pennants being confined near the yard by the crane-neck piece I, which slides down them, as the 90 yard is lowered, confine the center of the sail and compel it to fold in a backward direction in the space between the bunt pennants and the mast, thus pressing the wind entirely out of the center of the sail toward the leeches 95 thereof and causing it to come close up to and exactly opposite the center of the yard. Fig. 2 represents the condition of the sail when the yard is lowered and before the reef pennants are hauled tight; and it will be seen 100 that this condition of the sail is entirely different to that assumed by it at any stage of reducing or reefing with any other rig. The center of the sail being thus brought up snug to the yard, the drawing tight of the reef 105 pennants G, G, G, forces all the wind out of the leeches of the sail and brings the whole length of the sail close up to the yard plaited in front of the yard as shown in Fig. 3, in which condition it is secured by making fast 110 the ends of the reef pennants, ready for tying the reef points which may be brought around

the yard or secured to a jackstay as may be considered best. To spread the sail again the reef pennants are slackened and the yard hoisted up by the halyard.

5 It is not absolutely necessary to have a bunt pennant attached to every reef band, but a single bunt pennant attached to the lowest reef band passing through gromets attached to the other reef bands will serve 10 just as well.

The gromets attached to the upper reef bands will slide up and down the single bunt pennant and cause the sail to be plaited up as it runs down in the manner before described.

15 The use of flat blocks *c*, *c*, on the top of the yard instead of blocks suspended below as is the usual plan enables the sail to be drawn up to the top of the yard to confine the plaits in the bunt against the yard ready for tying 20 the points.

The invention may also be applied to top gallant sails and royals.

What I claim as my invention, and desire to secure by Letters Patent, is—

1. The arrangement of one or more bunt 25 pennants *H*, connected with the front of the sail, passing up the front thereof and connected with the yard, and of a crane-neck piece *L*, or its equivalent attached to the yard to work up and down said pennant or pennants, substantially as set forth, so that in lowering the yard the wind may be expelled from the bunt of the sail toward the sides, in the manner substantially as represented in Fig. 2. 30

2. The arrangement of the flat blocks *c*, *c*, through which the reef pennants run on the top of the yard, substantially as and for the purpose set forth. 35

THOMAS BATTY.
